22 Claims. (Cl. 178—79)

Type printing telegraphs employ as a rule trains, for example, of five current impulses for the transmission of the various signals. The keys of the transmitter control an appropriate number of permutation members which determine the operation of one or more transmitter contacts. If the permutation members are actuated directly by the keys, depression of the keys is made difficult and it has, on this account, been proposed that the permutation members should be displaced by springs controlled by the keys. With this system, a key, when depressed, lies in the path of one or more permutation members and allows or prevents the setting of the selected permutation members. The springs under the influence of which the permutation members are set are energized by a motor which also is used to control other parts of the type printing telegraph.

The purpose of the invention is to simplify the construction of such type printing telegraphs and, in particular, to avoid the necessity of providing a motor for controlling the various parts. In accordance with the invention, a magnet is provided which is energized before each transmission and thus sets the permutation members and energizes their springs. Furthermore, when a transmitter key is actuated, the permutation members are released by a control member common to all the keys so that they can be set by their springs. This is effected by putting the magnet temporarily out of action. Thus, the necessity for using a driving motor to avoid direct control of the permutation members by the keys is eliminated and the keys can be struck without being loaded by the permutation members. The common controlling member is preferably such that, on being actuated, it not only causes the magnet to be put out of action but also locks the permutation members in the position which they have assumed under the influence of the depressed key until the current impulse train has been transmitted.

An example of construction of a type printing telegraph in accordance with the invention is shown in the accompanying drawings in which:—

Figures 1a and 1b show in perspective the relative dispositions of the keys and the permutation members.

Figures 2 to 7 are detail views illustrating the positions taken up at various times by various parts of the apparatus and

Figures 8 and 9 show two suitable circuit arrangements for the actuation of the telegraph transmitter.

The various keys T1, T2 are mounted on a pair of pins TA1 and TA2 (Figure 1b) so that the shank of each key moves down substantially vertically when struck. A guide member L is associated with each key and underneath the guide members L there are five cranked bars SB pivotally mounted on the pins SBA. The bars SB have bent ends SK (Figure 1a) which engage under springs bk1—bk5. These springs tend to depress the ends SK and therefore to lift the parts of the bars SB which lie beneath the guide members L. When the magnet MAN is energized, its armature lifts the ends SK against the action of the springs bk1—bk5 and brings the parts of the bars SB lying beneath the keys out of range of the keys. The springs bk1—bk5 are contact springs, and are arranged so that the contacts controlled by them are reversed when the bars SB are moved. The bars SB also have hook shaped ends SP (Figure 1b) which can engage with the end PH of the armature MHA of a magnet MH.

A T-rail US and a further rail GS are disposed beneath guide members L which have gaps in them into which the rail US can enter. The rail US is under the action of a spring UF (Figure 1a) which tends to draw the rail forward (as seen in Figure 1) or to the left (as seen in Figures 2 to 7). The rail US is connected to the armature UA of a magnet U by a part UT joined to the armature at UG. This armature UA controls a pair of contacts u1 and u11, the contact u1 being actuated during the first part of the movement of the armature and the contact u11 only during the last part of the movement of the armature. The T-rail US can be influenced by each and every key, the rail GS only by two special keys TZ and TB which operate through the guide members LZ and LB and serve to effect the letter-figure and figure-letter shifts. The two keys swing the rail GS in opposite directions. The rail GS has a pin GA (Figure 1b) which drops into a resilient seat GR and thus holds the rail in one or the other of its two positions. The rail GS lies beneath the parts LP (Figure 2) of the guide members of one of the groups of keys, i. e., the letter keys or the figure keys, and thus prevents the keys of that group from being struck.

The lower part LK of the guide members L is serrated in accordance with the setting of the bars SB which it is to determine. The bars SB themselves could, of course, be serrated and the edge LK of the guide members L be plain. When a key is struck, some of the bars SB are held depressed against the action of their springs bk

while others are allowed by the gaps in the parts LK to move up under the action of their springs *bk*.

As already mentioned, the rail US can be turned on its pivot by each and every one of the guide members L. Figure 2 shows the guide member L₁ of a letter key and the guide member L₂ of a figure key and the common rails US and GS. The rail GS lies under the part LP of the guide member L₂ of the figure key so that only the letter key can be struck. The guide members, have extensions LU which can act on the common T-rail US. If, for example, the guide member L₁ is depressed, the rail US is swung to the right (Figure 2), sliding on the right hand surface of the extension LU. This surface has two parts sloping at different angles so that the rail US is moved in two steps, the first of comparatively great and the second of comparatively small magnitude. The pivotal movement of the rail US is transferred by means of the connecting member UT (Figure 1) through the joint UG to the armature UA, which, during the first part of its movement actuates its contact *u1* and closes a circuit for the magnet U so that the latter completes the attraction of the armature. This causes the rail US to swing clockwise (Figure 3) so that the head of its T leaves the side face of the extension LU and abuts 30 against the left hand face of an extension LR of the guide member L₁. When the key is fully depressed as is shown in Figure 3, the cross limb of the rail US enters a notch in the extension LR and as long as the rail US is held in this position, that is to say, as long as the armature UA remains fully attracted, the guide member and its associated key cannot be moved upwards. In this position, the contacts *u11* are also actuated by the armature UA for a purpose to be described 40 later on. When the rail US is in the notch in the extension LR of the depressed guide member, its cross limb lies beneath the extensions LR of the guide members of the other keys and prevents these keys from being depressed.

The guide members LB and LZ of the shift keys TB and TZ have the same extensions LU and LR as the guide members of the other keys. They are, however, constructed so as to be capable of actuating the rail GS so as to prevent actuation of one set of keys (letters or figures). For this purpose, the guide member LZ has an extension LG which, on being depressed, pivots the rail GS clockwise (Figure 5) while the left hand face of the extension LU is such that on being depressed, it pivots the rail GS counter-clockwise (Figures 6 and 7). The figure keys or the letter keys are thus prevented from being actuated.

The magnet MAN (Figure 1a) is always present 60 paratorily energized so as to remove the bars SB from the path of the guide members of the keys. As soon as a key has been completely depressed and the rail US can drop into the locking position, the contact *u11* is actuated by the armature UA and opens the circuit for the magnet MAN. The armature UA then drops and releases the bars SB. The bars which have notches opposite the depressed guide member can now be lifted by their springs *bk*; the others remain in the 70 pivoted position. The contacts controlled by the springs *bk* are now actuated in accordance with the combination to be sent out. A distributor is provided for transmission of the selected train of impulses. As soon as the train has been 75 transmitted, the magnet U is de-energized and

the rail US moves out of the locking position under the action of the spring UF. The depressed guide member and its key are released and are able to return into the normal position. In order to allow the depressed key to be re-set 5 earlier, a magnet MH is provided the energization of which is determined by the contact *u11*. The hook shaped extension PH of the armature MHA of this magnet engages in the hook ends SP of those of the bars SB which have been able 10 to return into their normal position and beneath the hook ends of the bars which remain in the displaced position. The setting of the bars SB and thus of the contacts actuated by the springs *bk* can be maintained independently of the position of the guide member of the depressed key, and the relay U can thus be de-energized as soon 15 as the magnet MH is energized.

In the circuit arrangement shown in Figure 8, the five contacts controlled by the bars SB are 20 designated *bk1*—*bk5*. The distributor controlling the transmission of the train of current impulses comprises six relays A to F controlled by a cadence tapper consisting of the relays N and O.

When a signal is to be transmitted, the key AT 25 is depressed so that the relay AN is energized and closes a holding circuit for itself at its contact *an1*. The contact *an2* closes the circuit for a thermo relay *Hi* which heats up slowly. If no signals are sent out within a pre-determined period of time, the relay *Hi* closes its contact *hi* and thus short circuits the relay AN which releases. The contact *an3* closes a circuit for the magnet MAN which responds and preparatorily pivots the transmitter bars SB (Figure 1). If, 35 now a key is depressed for the transmission of a particular signal, the rail US and the armature UA of the relay U coupled to the rail are pivoted through the guide member L. About midway through the movement of the key, the contact *u1* is closed by the armature UA and the relay U is thus energized and attracts its armature UA. The armature UA however cannot be brought into the attracted position until the key has been 40 fully depressed and the rail US can enter the 45 notch in the extension LR in the guide member. When this happens, the contacts *u11*, *u12* and *u13* corresponding to the contact *u11* shown in Figure 1 are reversed.

The contact *u11* closes a circuit for the winding 50 I of an auxiliary relay VS which is kept energized during the transmission of a signal by the contact *us3*. The contact *u12* closes the circuit for the transmitter relay S before relay US responds. The relay S controls the flow of current through 55 the line VL by means of its contact *s*. The contact *vs1* of the relay VS closes a circuit for the relay N of the cadence tapper. The contact *u13* opens the circuit for the magnet MAN so that the latter allows its armature to drop and releases the transmitter bars for displacement by their springs. The contacts *bk1* to *bk5* are thus actuated in accordance with the current impulse train associated with the depressed key. The magnet MH, the armature of which holds the 60 bars SB in the position they have assumed, is energized when the contact *vs4* closes.

The two relays O and N of the cadence tapper work like a relay interrupter. The relay N energizes the relay O and the latter opens the circuit for the relay N. The delay in response and release of the relay N is approximately 8 milliseconds and that of the relay O approximately 12 milliseconds. An interval of 20 milliseconds is therefore necessary for the successive energiza- 70 75 77

tion and de-energization of the two relays. Each impulse which is emitted by the relay S is also to have a duration of 20 milliseconds. At each response and at each release, the relay O actuates a relay of the chain of relays A-F. The relay A (winding I) was energized on response of the relay VS. By means of its contact *a1*, it closes a holding circuit through its winding II and also prepares a circuit for the relay B. If relay O responds after 20 milliseconds, the relay B is energized and, by means of contact *b1*, closes a holding circuit through its winding II and prepares a circuit for the relay C. If, after a further 20 milliseconds, the relay O releases, the circuit for the relay C is closed. In a similar manner, the relays A, B, C, D, E and F are energized successively at intervals of 20 milliseconds. Each of these relays determines one of the impulses to be sent out.

The relay A, in responding, opens the circuit for the relay S which was closed when the contact *u12* closed. This terminates the emission of the so-called "start" impulse which prepares the receiving devices at the other end of the line. The contact *a2* makes the circuit of the relay S dependent upon the contact *bk1*. If the position of the associated bar SB is such that this contact is closed, for example, the relay S is again energized and the line is again interrupted; otherwise, there is no energization of relay S and current flows through the line. The circuit for the transmitter relay S is now made successively dependent upon the contacts *bk2* to *bk5* by the relays B, C, D and E. In each case, the relay S remains under the influence of one of the contacts *bk* for a period of 20 milliseconds. A train of current impulses of uniform length is therefore transmitted by the contacts *bk*. Simultaneously with the energization of relay C which takes place on transmission of the third selecting impulse, a relay DR is energized and, by means of its contact *dr1*, interrupts the circuit for the relay U. The relay U allows its armature to drop, the rail US returns into the normal position and the depressed key can together with its guide piece move back into the normal position. The setting of the bars SB and of the contacts *bk* controlled by them is however maintained by the energization of the magnet MH. At the beginning of the transmission of the fifth selecting impulse, the relay E responds and, by means of its contact *e2*, opens the circuit for the magnet MH. The relay MH drops after a delay of approximately 20 milliseconds and, after the transmission of the fifth impulse, releases the transmitter bars SB so that they can drop back into their normal position. If the armature of the relay U has already dropped, the magnet MAN has already been energized again by way of the contact *u13*. As long as the bars SB are blocked by the armature of the magnet MH, the magnet MAN cannot attract its armature. As soon however, as this blocking has been released, the magnet MAN attracts its armature and preparatorily pivots the bars SB. At the end of the transmission of the fifth selecting impulse, the relay F is also energized, and, by means of its contact *f2*, opens the circuit of the auxiliary relay VS of the transmitter so that this relay drops and stops the cadence tapper. The contact *f3* opens the circuit for the transmitter relay S which drops and, by means of its contact *s*, establishes normal conditions in the line VL. The contact *f4* interrupts the holding circuit for the windings II of the relays A, B and C which drop

and thus interrupt the holding circuits through the windings II of the relays D, E and F. All the relays thus return to their normal position. The magnet MAN alone remains energized under the control of the starting relay AN. If there is no further signal transmission for a considerable time, this magnet also de-energizes on attraction of the thermo-relay HI.

The circuit arrangement shown in Figure 9 is substantially the same as that shown in Figure 8 except that the magnet MH which blocks the transmitter bars SB is omitted. For deenergizing the relay U on the transmission of the selecting impulses and thus releasing the blocking of the actuated key, two relays UR and VR are provided. The relay UR is controlled by the contact *bk4* and the relay VR by the contact *bk5*. The circuit of the transmitter relay S is not directly controlled by the contacts *bk4* and *bk5* upon the transmission of the fourth and fifth impulses but by the contacts *ur2* and *vr2* of the two relays UR and VR. The fourth and fifth impulses determined by the contacts *bk4* and *bk5* are stored by the relays UR and VR.

When, at the beginning of the signal transmission, the relay VS is energized, the contact *us5* closes the circuit for the relays UR and VR. If the selected combination is such that the contacts *bk4* and *bk5* are closed, both relays are energized and by means of their contacts *ur1* or *vr1* close holding circuits for themselves. If, on transmission of the third impulse, the relay U is de-energized by the energization of the relay DR and the depressed key is thus released, the key returns to its normal position and the bars SB are preparatorily pivoted again by energization of the magnet MAN. If the relays UR and VR in so far as they have been energized in accordance with the selected combination remain however energized independently of the contacts *bk4* and *bk5*, the transmission of the fourth and fifth impulse of the selected combination is ensured by contacts *vr2* and *ur2* and the holding circuit for the storing relays UR and VR is interrupted at the contact *f5* when the relay F responds after the emission of the fifth impulse.

We claim:

1. A telegraph transmitter comprising a plurality of transmitting keys, a plurality of permutation members influenced by said keys, springs acting on said permutation members, a magnet for displacing said permutation members against the action of their springs, a control member displaceable by each of said keys, means for energizing said magnet before each transmission, means controlled by said control means for temporarily putting said magnet out of action on actuation of one of said transmitting keys and means for emitting a train of current impulses determined by the setting of said permutation members.

2. A telegraph transmitter comprising a plurality of transmitting keys, a plurality of permutation members, springs acting on said permutation members and striving to move them against said transmitting keys, a magnet for displacing said permutation members against the action of their springs, a control member displaceable by each of said transmitting keys, means for energizing said magnet before each transmission, means controlled by said control member for temporarily putting said magnet out of action at each actuation of said transmitting keys, means controlled by said control member for locking said permutation members in the position which they

- assume under the influence of their springs when said magnet is put out of action, means for sending out a train of current impulses determined by the setting of said permutation members and 5 means for releasing said permutation members after transmission of said current impulse train.
3. A telegraph transmitter comprising a plurality of transmitting keys, a plurality of permutation members, springs acting on said permutation members and striving to move them against said transmitting keys, a magnet adapted to displace said permutation members against the action of their springs, a control member controlled by said transmitting keys, means for energizing 10 said magnet before each transmission, means controlled by said control member for temporarily putting said magnet out of action at each actuation of one of said transmitting keys, magnetically controlled means for locking an actuated transmitting key in the depressed condition and means for transmitting a train of current impulses determined by the setting of said 15 permutation members.
4. A telegraph transmitter comprising a plurality of transmitting keys, a plurality of permutation members, springs acting on said permutation members and striving to move them against said transmitting keys, a magnet for setting said permutation members against the action 20 of their springs, a control member controlled by said transmitting keys, means for energizing said magnet before each transmission, means controlled by said control member for temporarily putting said magnet out of action at each actuation of one of said transmitting keys, a magnet for locking an actuated transmitting key in 25 the depressed position and for holding the remaining keys against actuation and means for transmitting a train of current impulses determined by the setting of said permutation members.
5. A telegraph transmitter comprising a plurality of transmitting keys, a plurality of permutation members, springs acting on said permutation members and striving to move them against said transmitting keys, a magnet for setting said permutation members against the action of their springs, a control member controlled by said transmitting keys, means for energizing 30 said magnet before each transmission, means controlled by said control member for temporarily putting said magnet out of action at each actuation of one of said transmitting keys, a magnet for locking an actuated transmitting key in the depressed position and for holding the remaining keys against actuation and means for transmitting a train of current impulses determined by the setting of said permutation members.
6. A telegraph transmitter comprising a plurality of transmitting keys, a plurality of permutation members, springs acting on said permutation members and urging them against said transmitting keys, a magnet adapted to displace 35 said permutation members against the action of their springs, means for energizing said magnet before each transmission, a control member common to all said keys, a magnet acting on said control member and holding it in a position in which it locks an actuated transmitting key in the depressed position and holds the undepressed transmitting keys against actuation, contacts adapted 40 to be actuated by said control member in its lock- 45
- ing position whereby to put said first mentioned magnet out of action and means for transmitting a train of current impulses determined by the setting of said permutation members.
7. A telegraph transmitter as claimed in claim 5 1 comprising also contacts adapted to be actuated by the control member in its locking position whereby to bring into operation said current impulse transmitting means.
8. A telegraph transmitter comprising a plurality of transmitting keys, a plurality of permutation members, springs acting on said permutation members tending to move them against said transmitting keys, a magnet adapted to displace 10 said permutation members against the action of their springs, a transmission starting key, a contact controlled by said starting key, a holding relay controlled by said contact and adapted to close a circuit for the energization of said magnet, a control member common to all 15 said keys, a magnet acting on said control member and adapted to hold said control member in a position in which it locks an actuated transmitting key in the depressed position and to hold the unactuated transmitting keys in the raised 20 normal position, contacts adapted to be actuated by said control member in its locking position whereby to put said first mentioned magnet out of action and means for transmitting a train of current impulses determined by the setting of 25 said permutation members.
9. A telegraph transmitter as claimed in claim 8, comprising also contacts controlled by said transmitting keys during the depression of a transmitting key for energizing the magnet acting 30 on said control member.
10. A telegraph transmitter comprising a plurality of transmitting keys each provided with a guide member adapted to be displaced with its associated key, a plurality of permutation members, a spring acting on each of said permutation members and urging it against the guide member of a depressed transmitting key, a magnet for displacing said permutation members against the action of their springs, means for energizing said 40 magnet before each transmission, a contact adapted on actuation to de-energize said magnet, projections on said guide members, a rail adapted to act on said projections whereby to hold the guide member of an actuated transmitting key 45 in its displaced position and to preclude displacement of the guide members of the unactuated transmitting keys, a magnet for controlling the movement of said rail, means for energizing said magnet, said means being controlled by the guide 50 member of a transmitting key during the first part of the movement of said key controlled by said rail in its locking position for controlling said contact and means for transmitting a train of 55 current impulses corresponding to the setting of 60 said permutation members when freed by said magnet.
11. A telegraph transmitter as claimed in claim 10 comprising also means for putting out of action said rail controlling magnet after said current impulse train has been transmitted.
12. A telegraph transmitter as claimed in claim 10 comprising also means for locking said permutation members in the position which they assume under the influence of their springs after their setting magnet has been put out of action, said means being controlled by said impulse transmitting means during the transmission of said train, means for putting out of action said rail controlling magnet, said means being controlled

5 by said current impulse transmitting means after actuation of said permutation member locking means, and means for releasing said permutation members after the transmission of said current impulse train.

13. A telegraph transmitter comprising a plurality of transmitting keys each provided with a guide member, a plurality of permutation members, springs acting on said permutation members and urging them against the guide member of a depressed transmitting key, contacts controlled by said permutation members, a magnet for displacing said permutation members against the action of their springs, means for energizing said magnet before each transmission, means for locking the guide member of a depressed transmitting key, said means preventing movement of the guide members of the undepressed keys, a contact controlled by said last-mentioned means for putting out of action the magnet for displacing the permutation members, means for transmitting a train of current impulses corresponding to the setting of said contacts controlled by said permutation members and means controlled by said guide member locking means adapted to put said current impulse transmitting means into action.

14. A telegraph transmitter as claimed in claim 13, in which said permutation member contacts 30 are carried by the springs acting on said permutation members.

15. A telegraph transmitter comprising a plurality of transmitting keys each provided with a guide member, a plurality of permutation members, springs acting on said permutation members and urging them against the guide member of a depressed transmitting key, contacts controlled by said permutation members, a magnet for displacing said permutation members against the action of their springs, means for energizing said magnet before each transmission, means for locking the guide member of a depressed transmitting key and for preventing actuation of the undepressed keys, a contact controlled by said last-mentioned means for putting out of action the magnet for setting the permutation members, a current impulse transmitting relay, a distributor connecting said transmitting relay successively in circuits dependent upon the various contacts controlled by said guide member locking means for putting said distributor into action.

16. A telegraph transmitter comprising a plurality of transmitting keys each provided with a guide member, a plurality of permutation members, springs acting on said permutation members and urging said permutation members against the guide member of a depressed transmitting key, contacts controlled by said permutation members, a magnet for displacing said permutation members against the action of their springs, means for energizing said magnet before each transmission, means for locking the guide member of a depressed transmitting key and for preventing movement of the guide members of the undepressed keys, a contact controlled by said last-mentioned means for putting out of action the magnet for setting the permutation members, storing relays controlled by the contacts of some of said permutation members, a current impulse transmitting relay, a distributor adapted to connect said transmitting relay successively in circuits dependent upon said permutation member contacts and in circuits dependent on said

storing relay contacts and means controlled by said guide member locking means for putting said distributor into action.

17. A telegraph transmitter as claimed in claim 16, comprising also means for releasing said guide members after energization of said storing relays and means for putting said storing relays out of action after transmission of a current impulse train determined by the setting of said permutation members.

18. A telegraph transmitter comprising a plurality of transmitting keys each provided with a guide member, a plurality of permutation members, springs acting on said permutation members and urging them against the guide member of a 15 depressed key, a control member controlled by said guide members on depression of the associated transmitting key, a magnet having an armature connected to said control member, a plurality of contacts controlled by said armature, 20 said control member being adapted to bring said armature near the pole of said magnet on being actuated by the guide member of a transmitting key, a contact adapted to be actuated by said armature in being thus brought near said pole 25 and adapted on such actuation to energize said magnet, said armature being adapted on being attracted to said pole to swing said control member into a position in which it holds the guide member of a depressed key and precludes movement 30 of the guide members of the remaining keys, a further magnet for displacing said permutation members against the action of their springs, means for energizing said further magnet before each transmission, a contact adapted 35 to de-energize said magnet on being actuated by said armature when it reaches the pole of its magnet, means for transmitting a train of current impulses corresponding to the setting of said permutation members under the influence of 40 their springs, means actuated by said armature when it strikes the pole of its magnet for putting said current impulse transmitting means into action, and means for putting said magnet out of action controlled by said current impulse transmitting means after transmission of said current impulse train.

19. A telegraph transmitter comprising a plurality of transmitting keys each provided with a guide member, a plurality of permutation members, springs acting on said permutation members and urging them against the guide member of a depressed key, a control member controlled by said guide members on depression of the associated transmitting key, a magnet having an armature connected to said control member, a plurality of contacts controlled by said armature, 50 said control member being adapted to bring said armature near the pole of said magnet on being actuated by the guide member of a transmitting key, a contact actuated on such movement of said armature whereby to energize said magnet, said armature on being attracted to said pole being adapted to swing said control member into a position in which it holds the guide member of a 55 depressed key and precludes movement of the guide members of the remaining keys, a further magnet for displacing said permutation members against the action of their springs, means for energizing said further magnet before each transmission, a contact adapted to de-energize said further magnet on being actuated by said armature when it strikes the pole of its magnet, a current impulse transmitting relay, contacts controlled by said permutation members, a distrib- 70 75

5 utor connecting said transmitting relay success-
sively in circuits dependent upon said permuta-
tion member contacts, a contact controlled by
said armature for putting said distributor into
action and means controlled by said distributor
for putting said first mentioned magnet out of
action.

10 20. A telegraph transmitter as claimed in claim
19, comprising also a magnet for locking said
permutation members in the position which they
assume under the influence of their springs,
means for switching in said magnet, said means
being controlled by the contact of the armature
connected to the control member when it strikes
15 the pole of its magnet, means actuated by said
distributor during the transmission of the cur-
rent impulse train for putting said magnet out
of action and acting on said control member
and means actuated by said distributor after
20 the transmission of said current impulse train
for putting out of action the magnet controlling
said permutation members.

21. A telegraph transmitter comprising two groups of transmitting keys, two shift keys, guide members connected to said transmitting keys and to said shift keys, a plurality of permutation members, springs acting on said permutation members and urging them against the guide

member of a depressed key, a magnet for displacing said permutation members against the action of their springs, a control member adapted to be actuated by the guide members of all said keys, means for locking the guide member of a depressed key and for preventing movement of the guide members of the remaining keys, said means being actuated by said control member on being actuated by a guide member of a key, means actuated by said locking means for putting said magnet out of action, a rail controlled by said two shift keys and always locking one of said groups of transmitting keys and means for transmitting a train of current impulses corresponding to the setting of said permutation members under the influence of their springs. 15 15

under the influence of their springs.

22. A telegraph transmitter as claimed in claim 21, in which the guide members of the two groups of transmitting keys are provided with various projections and in which the rail controlled by the two shift keys is pivotally mounted beneath the guide members of the transmitting keys and lies in each of its two positions in the path of movement of said projections of the guide members of one of said groups of transmitting keys. 25
